LINE PULSE MODULATOR

John E. Gorham, Spring Lake, and Walter T. Silver, Belmar, N. J., assignors to the United States of America as represented by the Secretary of War

Application July 6, 1944, Serial No. 543,742

16 Claims. (Cl. 250—17)

(Granted under the act of March 3, 1883, as amended April 30, 1928; 370 O. G. 757)

1

The invention described herein may be manufactured and used by or for the Government for governmental purposes, without the payment to us of any royalty thereon.

This invention relates to keying circuits for radio transmitters, and more particularly to the keying circuits which periodically key transmitters by means of pulses of short duration.

The invention will be described by way of an example in connection with radio object locating systems, but it is obvious that the invention has a wider utility, and may be used with any type of pulse-modulated radio transmitters.

In the radio object locating systems the transmitted exploratory pulses, are, as a rule, of extremely short duration and of the highest obtainable power, the effective operation of the systems depending to a very large extent on the power of the transmitted exploratory pulses. This type of operation of transmitting channels requires very large concentration of power during short periods of time, and the task of delivering this power to the transmitters evolves upon the keyers, since plate modulation of the transmitters' oscillators is assuming an increasingly dominant position in operating the pulse-modulated radio systems.

The invention discloses three keyers which are capable of handling very large currents, are stable in operation, light in weight, and use components which do not differ from standard components currently used in many industrial controls of power, thus facilitating their procurement and decreasing many fold the total cost of the keyers which heretofore required specially built, expensive equipment.

In accordance with the embodiment of this invention, use is made of relatively simple pulse-generating circuits, which are periodically discharged through a mercury pool type gaseous tube generally known in electrical power industry as "ignitron." Since "ignitrons" require periodic ignition, circuits are provided to accomplish this purpose, two periodically discharging artificial lines being used respectively for igniting the "ignitron" and for generating the keying pulse for the transmitter. A direct current source is used for periodically charging a first artificial line, and, upon the line being fully charged, discharging it very quickly through low impedance of a thermionic tube which is rendered conductive for this purpose by positive pulses impressed on its control grid. The first artificial line is connected in series with the primary of a pulse transformer, the secondary of

2

which is connected in series with the ignitor-cathode circuit of the "ignitron." Thus the energy necessary for producing the ignition in the "ignitron" is supplied by the energy stored in the first artificial line during its charging period. The "ignitron" itself acts periodically as a low impedance path for the second artificial line connected on one side to a high potential source, and to the primary of a pulse transformer on the other side. The secondary of this pulse transformer is connected to an oscillator in the transmitter. The "ignitron" periodically shunts the series circuit formed by the second artificial line and the primary of the pulse transformer so that the energy stored in the second line is discharged through the "ignitron" and through the pulse transformer, thus delivering the necessary keying pulse to the transmitter.

The advantages of such arrangement reside in the fact that very large amounts of energy may be stored in the artificial lines during relatively long charging periods, the changing rates of the two artificial lines being so slow that they do not result in the generation of any effective pulses in the pulse transformers, and discharging the stored energies at such a rapid rate that two very powerful pulses are produced, one of which is utilized for producing the ignition in the "ignitron," while the other pulse is used for keying the transmitter. Since the required power is thus obtained by storing it in the artificial lines, large quantities of power, in the order of one megowatt or larger, may be produced with very light equipment requiring only a small number of tubes and devoid of bulky sources of power. A single tube, an "ignitron," is used for actually delivering this large power to the transmitter. An additional advantage of the invention resides in the fact that extremely accurate control of the ignition pulses, as well as of the keying pulses, is obtainable since the time constant of the artificial lines may be readily computed and maintained without any further adjustments or complex apparatus for maintaining their stability. Thus the ignition and the transmitted pulses, the duration of which is in the order of only a fraction of one microsecond, are obtainable and the length of even such short pulses may be adjusted, if there is any need, with the precision of one-hundredth of a microsecond (10^{-8} sec.).

In order to lighten the power source still further, the charging circuit of the second artificial line, connected to the transmitter, includes a high inductance choke coil, this choke coil and

the artificial line forming a resonance circuit so that the charging voltage impressed on the artificial line by the potential source takes the form of an oscillatory transient, the positive peak of which is equal to twice the voltage of the positive source of potential connected to the line.

According to another embodiment of the invention, two "ignitrons" are connected in series for discharging the artificial line connected to the transmitter, the two "ignitrons" acting as voltage dividers thus allowing to double the maximum charging voltage which divides itself between the two "ignitrons."

In the last embodiment of the invention, Figure 5, the first artificial line has been eliminated and the ignition in the "ignitrons" is produced directly by the pulse generating circuits.

It is, therefore, the principal object of our invention to provide a keying circuit which uses "ignitrons" for discharging an artificial line, the line representing the component part of the keying circuit and controlling the duration of the transmitted pulses.

Another object of our invention is to provide a novel ignitor-electrode circuit for an "ignitron" in which the pulses impressed on the ignitor electrode are carefully timed so as to avoid rapid burning out of the ignitor electrodes even when the "ignitrons" are subjected to continuous operation.

An additional object of our invention is to provide a keying circuit in which an artificial line, an inductance, and an output transformer form a resonant circuit, making it possible to use a low voltage power supply.

The novel features which we believe to be characteristic of our invention are set forth with particularity in the appended claims. Our invention itself, however, both as to its organization and method of operation, together with the further objects thereof, may be best understood in connection with the following description in connection with the accompanying drawing in which:

Figure 1 is a block diagram of a transmitted channel.

Figure 2 is a schematic diagram of a keyer using one "ignitron."

Figure 3 is a schematic diagram of a keyer using two "ignitrons."

Figure 4 is an oscillogram of an artificial line charging current, and

Figure 5 is a schematic diagram of a keyer using two "ignitrons," the ignition of which is accomplished directly by the pulse generating circuits.

Referring to Fig. 1, an amplifier 10 is connected by means of a conductor 12 to a source of periodic pulses 11 obtained by connecting an oscillator to overdriven amplifiers and differentiating networks capable of transforming the sinusoidal wave into a series of pulses of one polarity. The same result may be obtained by connecting a self-damped oscillator to multivibrator circuits, the output of the latter being again connected to a differentiating network and pulse forming amplifiers. For a more detailed description of the pulse generating circuits, reference is made to a patent application of William A. Huber and William T. Pope, Jr., Serial No. 506,808, filed October 19, 1943, titled "Radio Object Locating System," and to a patent application of William A. Huber titled "Radio System," Serial No. 543,745, filed July 6, 1944. Normally, amplifier 10 is nonconductive, this nonconductive period being utilized for fully

charging an artificial line 14 whereupon pulse 11 is impressed on the control grid of amplifier 10 making it fully conductive, the artificial line 14 discharging to ground on one side through amplifier 13 and through the primary of a pulse transformer 16 on the other side. The secondary of transformer 16 is connected in series with the ignitor electrode-cathode circuit of an "ignitron" keyer 18. The "ignitron" is normally nonconductive, allowing an artificial line 20 to be charged to the highest obtainable charge. Upon reaching this maximum charge, the artificial line is discharged through the "ignitron" keyer 18, the latter being rendered conductive at this instant by the pulse impressed on the ignitor electrode-cathode circuit by the artificial line 14. The artificial line 20 is so positioned in the circuit of the transmitting channel that while it discharges on one side through the "ignitron" keyer 18, it discharges on the other side through the primary of a pulse transformer 22. The secondary of transformer 22 is connected in series with the oscillator of a transmitter 24. It is the discharge of the artificial line 20 that finally supplies the necessary keying pulses to the oscillator of transmitter 24, the latter sending an exploratory pulse over an antenna array 26.

Referring now to Fig. 2, where the same numerals are used for designating the same elements, amplifier 10 is a three-element tube, preferably of gas-filled type, which is so biased that it is normally nonconductive. The plate of triode 10 is connected to a D. C. source 206 over a conductor 204 and a choke coil 205, the latter deionizing triode 10 after discharge period of artificial line 14. The amplifier is shunted to ground by artificial line 14 and the grounded primary of pulse transformer 16. When triode 10 is nonconductive condensers 200 are charged to a voltage of that portion of the potential source 206 which is connected to the anode of triode 10; at this instant a positive pulse 11 is impressed on the control grid of triode 10 making it conductive, and line 14 is discharged through the cathode-anode circuit of the triode on one side, and through the primary of transformer 16 on the other side. The discharge of line 14 impresses the necessary ignition pulse on the ignitor electrode 208 producing the desired ionization of the ignitron. The pulses impressed on the ignitor circuit are of extremely short duration, for example, in the order of one microsecond, the duration of these pulses being timed by means of line 14 which is designed to discharge during this one microsecond. The impedance through which line 14 discharges itself is made equal to the impedance of line 14 to avoid any reflections so that the pulses impressed on electrode 208 are very sharp rectangular pulses 209. In order to avoid distortion of the pulses in the primary and secondary of transformer 16 this transformer is made according to the known practice for making pulse transformers. For a more detailed description of the behavior and the design formulae for the artificial line 14, which is sometimes called a Guillemin line, reference is made to Chapter 5 and especially to, "Foster's Theorem" vol. 2, "Communication Networks" by E. A. Guillemin, published by John Wiley and Sons, Inc., 1935. For a more detailed description of the design of pulse transformers, reference is made to an article titled "Iron Core Components in Pulse Amplifiers" by Reuben Lee, "Electronics," August, 1943, vol. 16, p. 115.

Proceeding now with the description of the ig-

nitron keyer itself, it begins with a series circuit of a grounded source of potential 206, a choke coil 214, an artificial line 20, and the primary of pulse transformer 22. Line 20 is periodically charged by 206 through coil 214 and the primary of transformer 22, this charging circuit forming a resonant circuit so that the charging voltage and current follow an oscillatory transient path illustrated in Fig. 4. The maximum voltage impressed on line 20 is equal approximately to twice the voltage of source 206, or voltage 2E illustrated in Fig. 4, after a period of time, T, which may be in the order of 500 microseconds, or longer. The primary of transformer 22 and line 20 are shunted by the cathode-anode circuit of ignitron 212, the ignitron being nonconductive during the charging period of line 20. The ignition of the ignitron, as described previously, establishes an arc between the cathode and the ignitor electrode, and, because of the high positive potential 2E impressed at this instant on the anode of the ignitron, the latter becomes practically instantaneously fully ionized, thus discharging line 20 to ground through its cathode-anode circuit on one side and through the primary of transformer 22 on the other side. The discharge of the line impresses the desired pulse on the secondary of transformer 22 and transmitter 24 which results in transmission of an exploratory pulse over antenna 26. As in the case of line 14, the impedance of the primary of transformer 22 and the cathode-anode impedance of the ignitron 212 are adjusted so as to match the impedance of line 20, the matching being necessary to avoid any wave reflections which obviously can not be tolerated in the described circuits.

It is a very well known phenomenon in connection with the ignition of "ignitrons" that even when the ignition pulses impressed on the ignitor electrode are very carefully timed and their magnitudes controlled, there may be slight difference in time of actual ionization of the ignitrons, or, more specifically, the time between the application of the voltage pulse and establishing of an arc between the mercury pool and the bracket holding the ignition electrode is not a constant. The arc between cathode and anode forms almost immediately upon ignition, closing the anode circuit in a very small fraction of a microsecond after the arc first bridges the mercury pool with the ignitor bracket. But the ignition time per se varies from cycle to cycle, the variations following a simple statistical law. In the operation under discussion, however, the rectangular pulse 209 creates a potential gradient much greater than the critical ignition voltage value, and, as a consequence, the variations in time of the establishment of the arc is only in the order of a small fraction of a microsecond.

The question arises whether this variation in the ignition time of the ignitron is of such magnitude as to require positive synchronization between the triggering pulses 209 impressed on the ignitor electron 208 and the charging cycle of the Guillemin line 20. Comparison of the time constants involved immediately reveals the fact that such synchronization is unnecessary. Because of the very high inductance of coil 214, which may be in the order of 100-200 henrys, the value of inductance 214 depending upon the desired time constant of the Guillemin line with which it forms a resonant circuit, the duration of the voltage half-cycle T, Fig. 3, may be in the order of 500 microseconds. This value of 500 microseconds compares so favorably with a fraction of a

microsecond, which is the maximum variation in the ignition time, that any synchronization, other than the proper timing of the Guillemin line and of the inductance 214, is obviously unnecessary.

Summarizing the operation of the keying circuit illustrated in Fig. 2, line 14 is slowly charged by source 206, the charging current producing no ionization in ignitron 212 because of the slow charging rate. When the line becomes fully charged, the positive rectangular pulse 11 makes triode 10 fully conductive discharging the Guillemin line 14 through the low impedances of triode 10 and through the primary of transformer 16, the latter impressing the ignition pulse on the ignitor 208. Prior to this instant, the second artificial line 20 has been fully charged by the same source 206, and immediately upon the establishment of the hot spot on the mercury pool 210, ignitron 212 flashes over and discharges line 20 through the primary of transformer 22. This impresses the desired pulse on transmitter 24. The inductance of the choke coil is sufficiently high to preclude the continuance of the ionized state in ignitron 212 after line 20 has been discharged. Therefore, upon the discharge of line 20 ignitron 212 becomes deionized and the operating cycle of the keyer repeats itself.

The following circuit constants and tubes give satisfactory operation of the keyer shown in Fig. 3 with a 20-microsecond exploratory pulse:

D. C. source 206, 8,000 volts
Inductance 214, 40 henrys
Artificial line 20:
Condensers, .04 microfarad
Coils, 67.5 microhenrys each
Time constant, 20 microseconds
Transformer 22, 1 to 3 step-up ratio, "Hypersil" core
Modulation pulse impressed on transformer 24,
1.5 megawatts
Ignitron 212, GL 415, G. E. Co.
Artificial line 14:
Condensers, .003 microfarad each
Coil, 11.5 microhenrys each
Time constant, 1.5 microseconds
Coil 205, 500 henrys
Triode 10, 4C35
Transformer 16, 2 to 1 step-down ratio, "Hypersil" core

Fig. 3 discloses a keyer which is similar in all respects to the keyer of Fig. 2 with one exception: two ignitrons 300 and 302 are connected in series and are shunted by two resistors 304, 306. The resistors connect the junction point between the choke coil 214 and line 20 to ground and act as positive means for equally dividing the maximum voltage impressed on the ignitrons. Two artificial lines 308 and 310, two pulse transformers 316 and 318, and two triodes 312 and 314 are used on the input side of the keyer. The secondaries of the transformers 316 and 318 are connected across the cathode-ignitor circuits of the ignitrons 300 and 302. The functioning of this circuit is otherwise similar in all respects to the functioning of the circuit disclosed in Fig. 2. Pulses 11 are impressed on the control grid of triode 312, the latter being normally nonconductive. The grid of triode 314 is connected to a cathode resistance 320, this connection making triode 314 to follow triode 312. Accordingly, pulse 11 renders the two triodes conductive simultaneously so that their artificial lines 308 and 310 discharge simultaneously through triodes 312 and 314 on one side, and through the primaries

of transformer 316 and 318 on the other side. The two ignitrons become conductive simultaneously and the artificial line 39 is discharged to ground through the two ignitrons in series.

As mentioned previously two ignitrons in series are used in Fig. 3 to double the voltage impressed on the artificial line 20 in Fig. 3. Since the mercury pools in the ignitrons establish some mercury vapor pressure within the evacuated chambers of the ignitrons, they can withstand only a certain voltage whose value is determined by the geometry of the tube and vapor pressure, any higher voltage producing flash-over from the cathode to the anode. When the transmitter's power must be increased, one of the most convenient methods of accomplishing this result is by increasing the voltage impressed on the artificial line 20. When this voltage begins to exceed the flash-over value to use of a single ignitron, as illustrated in Fig. 2, becomes impossible and a voltage dividing circuit, such as that shown in Fig. 3, must be used. The circuit constants for the keyer, illustrated in Fig. 3, are the same as those which were quoted for Fig. 2 except that the voltage of source 306 has been doubled. The resistors 304 and 306 are each 10 megohm resistors. It may be added here that the resistors 304 and 306 are used to insure a more equal division at all times of the total voltage between the two ignitrons, thus insuring the normal operation of the ignitrons and preventing accidental flash-overs.

Actual operation of the ignitrons in the keying circuits has disclosed the fact that the most sensitive element in the entire circuit is the ignitor electrode used for establishing the hot spot on the mercury pool of the ignitrons. As is well known in the art, the radio locators, as a rule, operate continuously over long periods of time, this type of operation being especially common in connection with radio locators assigned for continuous routine surveillance of the assigned areas. Since the establishment of ignition must take place in an extremely short period of time, very large power must be delivered to the ignitor electrode, the cumulative effect of this type of operation eventually resulting in premature burning out of the ignitor electrode. It also has been discovered that the life of the ignitor electrodes, and, as a consequence, of the entire keyer, may be increased many fold if precautions are taken to prevent in some very positive manner the ignitor electrode from carrying any current immediately upon the establishment of the main cathode-anode circuit.

In the disclosed keying circuits the life of the ignitor electrode is protected by interposing the artificial line 14 in Fig. 2 and the artificial lines 308 and 310 in Fig. 3, between the triodes and the pulse transformers 16, 316 and 318. Thus, the timing of the ignition pulse impressed on the ignitor electrode does not depend on the timing of the rectangular pulses 11, but on the parameters of the artificial lines. Since the artificial line constants may be maintained quite constant, it is possible to adjust the rectangular pulses impressed on the ignitors so that they hardly carry any parasitic currents. This is especially true in view of the discovered fact that the variations in the ignition time or "jitter" decrease very rapidly with the shortening of the ignition period; thus, with the ignition pulse in the order of 1 microsecond, the "jitter" is reduced to a very small fraction of a microsecond,

which for practical purposes eliminates the parasitic currents.

Figure 5 discloses another modification of a line pulse modulator, the keying circuit itself being identical with the keying circuit disclosed in Fig. 3. For this reason it is not shown in Fig. 5 but the connections of ignitrons 300 and 302 may be completed by matching the dotted lines A—A in Figs. 3 and 5. The modification resides in the elimination of lines 308, 310 and the ignitor electrodes are now connected directly to a pulse transformer 500, the primary of which is connected to a pulse amplifier 502. The remaining connections are self-explanatory. Amplifier 502 is normally nonconductive because of the negative biasing potential. Positive pulses 504 make it conductive, which in turn ionizes ignitrons 300 and 302.

The most important advantages of the disclosed line pulse modulators are the idle time periods between the keying pulses impressed on the transmitter which may be very carefully timed, and pulses of extremely short duration, from a fraction of one microsecond and up, may be generated; the modulation pulses possess very large power, such as 1.5 megawatt or higher, and the stability of the pulses from the points of view of timing and power impressed on the transmitter is very high, only minor timing variations being introduced by the jitter.

In Figures 3 and 5 only two ignitrons, connected in series for discharging the Guillemin line, are illustrated. When still higher voltages and higher modulation power are desired, it is obvious that the configuration of the circuit is such that it lends itself very readily to any desired multiplication of the number of ignitrons in the series circuit. In Figure 3 the multiplication of the number of ignitrons would require a corresponding multiplication in the number of the artificial lines, or, construction of a single line, which would be capable of delivering the necessary energy for producing the ignition in all ignitrons, the connections in the latter case being as those illustrated in Figure 5 with the exception that an artificial line would be interposed between triode 502 and the primary of transformer 500. In Figure 5 the multiplication of the number of ignitrons in the keying pulse generating circuit will call for no other change but the corresponding multiplication of the secondaries in the transformer 500 and of the resistances 304. Obviously enough large power will have to be delivered by triode 502 which may necessitate paralleling several triodes.

Ignitrons have almost unlimited peak current-carrying capacity (several thousand amperes or more). As a consequence, a more practical method of increasing the power of the keying pulse would lie in the direction of lowering the impedance of the pulse forming line in the main power pulse circuit, and increasing the set-up ratio of the transformer connected to the transmitter. This arrangement is obviously more economical than the one calling for the multiplication of the ignitrons since it takes full advantage of the peak current-carrying capacity of the ignitrons.

Circuits are also disclosed which offer high degree of protection for the ignitor electrodes resulting in the prolonged life of this element which otherwise is the weakest point in the system. An additional advantage typical of the circuits disclosed in Figs. 2 and 3 resides in the fact that extremely low average power requirements are

imposed on the pulse generating circuits, connected to the ignitor-cathode circuit of the ignitrons, for two reasons: first, the duration of the ignition pulses 289 is in the order of one microsecond, and second, the required power is supplied by the artificial lines. As in the case of the main artificial line 26 the auxiliary artificial lines 14, 308, and 319 may also form a resonant circuit with the result that the charging voltage impressed on these lines is along the oscillatory path illustrated in Figure 4. Accordingly, large power may be accumulated in these ignition pulse generating circuits with a relatively limited power supply, the power limiting factor of the ignition pulse generating circuit being, in the main, the current carrying capacity of the triodes which shunt the lines to ground. Since the current carrying capacity of the gas-filled tubes is higher than the current carrying capacity of the vacuum tubes, the triodes 10, 312, and 314 are shown to be gas-filled triodes.

From the description of the line pulse modulator it is quite apparent that the only power limiting factor in the line pulse modulators is the Guillemin line, and the source of potential 206 or 306, the remaining components of the keying circuit per se being capable of carrying very large currents. This is especially true of the ignitrons. In the prior art the modulator tubes always constituted the power limiting element in the modulators whenever large power requirements were imposed upon the modulators. The disclosed modulators solved this difficulty very successfully since the current carrying capacity of the ignitrons is limited only by the capacity of their cooling systems, the latter permitting currents in the order of 5000 amperes or higher.

It is believed that the construction and operation of our new line pulse modulators, as well as the advantages thereof, will be apparent from foregoing description. It will, therefore, be apparent that while we have shown and described our invention in several preferred forms, many changes and modifications may be made without departing from the spirit of our invention as sought to be defined in the following claims.

We claim:

1. A keyer for a radio transmitter including a series circuit of a source of potential, an impedance, an artificial line, and means interconnecting said artificial line to said transmitter, said series circuit comprising a resonant network, and a gas-discharge tube path shunting said artificial line and said means, said tube path periodically discharging said artificial line for generating keying pulses through said means for said transmitter.

2. In a keying circuit for a transmitter, a series resonant circuit including a source of potential, a choke coil, an artificial line, and a coupling means, said coupling means electrically coupling said series circuit to said transmitter, and said source of potential periodically charging said line, a gas-discharge tube path shunting said artificial line and said coupling means, and a source of pulses rendering said tube path conductive in synchronism with the appearance of the maximum charge on said artificial line.

3. In a keying circuit for a transmitter, a coupling means between said keyer and said transmitter, a serially connected artificial line and a choke coil, said choke coil being connected to a source of potential, and said line being connected to said coupling means, said source of potential

periodically charging said artificial line, a gas-discharge tube having a cathode, an anode, and an igniter electrode, the cathode-anode circuit of said tube serving to shunt said artificial line and said coupling means, and a source of pulses rendering said tube conductive in synchronism with the appearance of the maximum charge on said artificial line, said artificial line, choke coil, and said means forming a series resonant circuit, and said choke coil forming a deionizing means for said tube.

4. A line pulse modulator for a radio transmitter including a radio transmitter, a source of potential, an artificial line connected to said source of potential through an impedance and to said transmitter through a coupling means, said source, line, impedance, and coupling means being connected in a series resonant circuit, a gas-discharge triode including a mercury pool cathode, an anode, and an igniter electrode, the cathode-anode circuit of said triode serving to shunt said artificial line and said means, and a source of pulses connected across said cathode and said igniter electrode for producing ionization in said triode whereby said artificial line discharges through said triode and through said means, the discharges of said line generating modulation pulses for said transmitter.

5. A line pulse modulator connected to a transmitter, said modulator including a series circuit of a source of potential grounded with its negative terminal, a choke coil, an artificial line and a primary of a step-up transformer, the secondary of said transformer being connected to said transmitter, said series circuit forming a series resonant network, and the input impedance of said transformer substantially matching the characteristic impedance of said artificial line, a gas-discharge tube connected between ground and the junction point between said choke coil and said artificial line, and a source of periodic pulses connected to said tube, said pulses and said artificial line rendering said tube periodically conductive whereby said line discharges through said tube and through the primary of said transformer, the discharges of said line through said transformer producing keying pulses for said transmitter.

6. A keyer for a radio transmitter as defined in claim 5 in which said gas-discharge tube comprises a triode including a mercury pool cathode, an igniter electrode, and an anode, said source of pulses being connected across the igniter electrode-cathode circuit of said triode.

7. A keyer for a radio transmitter as defined in claim 5 in which said source of pulses includes a second periodically charged and discharged artificial line, the discharge of said second line generating said periodic pulses.

8. A keyer for a radio transmitter as defined in claim 5 in which said tube comprises a triode including an ionizable reconstructive cathode, an ignitor electrode, and an anode, and said source of pulses further comprises a source of periodic signals, a second gas-discharge tube which also comprises a triode including a cathode, a control grid and an anode connected with its grid to said source of signals, said signals periodically rendering said second triode conductive, a second artificial line connected with one end to the anode of said second triode, and a coupling means connected to the other end of said second line, said means connecting said second artificial line to the ignitor electrode-cathode circuit of the first gaseous triode.

11

9. A line pulse modulator comprising a first series resonant circuit including a grounded source of potential, a choke coil, an artificial line, and a primary of a transformer, said artificial line and said primary being shunted by a gas-discharge tube having a cathode, a control grid, and an anode, said anode being connected to a conductor interconnecting said choke coil and said artificial line, a source of periodic pulses connected to said control grid rendering said tube periodically conductive for discharging said artificial line through said tube and through said transformer, a second series circuit including a source of potential, a second choke coil, a second artificial line, and a primary of the second transformer, a second gas-discharge tube shunting said second artificial line and the primary of said second transformer, said second tube having a pool of ionizable reconstructive cathode material, an anode, and an ignitor for said cathode, the cathode-ignitor circuit of said second tube being connected across the secondary of said first transformer, and a transmitter connected to the secondary of said second transformer, said first and second series circuits and said tubes being so constructed and arranged that said first series circuit periodically produces an active cathode area in said second tube, and said second series circuit periodically produces modulating pulses for said transmitter.

10. A line pulse modulator including a series resonant circuit comprising a source of potential, an impedance a network capable of storing electrical energy, and coupling means connecting said network to a transmitter, an ignitron having an ionizable reconstructive cathode, an ignitor electrode, and an anode, the cathode-anode circuit of said ignitron shunting said network and said coupling means, and a source of periodic pulses having a duration in the order of from 0.5 to 10 microseconds connected across the cathode-ignitor circuit of said ignitron, said pulses establishing an active area on said cathode for shorting said network through said ignitron and through said coupling means for generating modulation signals for said transmitter.

11. A keyer for a radio transmitter including a series resonant circuit of a source of potential, an impedance, an artificial line and a coupling means, said coupling means connecting one end of said artificial line to said transmitter, and two serially connected ignitrons shunting said artificial line and said coupling means, said ignitrons periodically discharging said artificial line through their cathode-anode circuits and through said coupling means for generating keying pulses for said transmitter.

12. A keyer for a radio transmitter as defined in claim 11 which further includes two serially connected resistances, one of said resistances shunting the cathode-anode circuit of one ignitron and the other resistance shunting the cathode-anode circuit of the other ignitron.

13. A keyer for a radio transmitter as defined in claim 11 which further includes a source of periodic pulses connected to the ignitor-cathode circuit of each ignitron, said source being capable

12

of establishing substantially simultaneously active cathode areas in said ignitrons.

14. A keyer for a radio transmitter as defined in claim 11 which further includes a source of periodic pulses, a vacuum tube amplifier connected to said source, and a transformer having one primary and two secondaries, said primary being connected to said amplifier, and said secondaries being connected across the ignitor electrode-cathode circuits of said ignitrons respectively.

15. A keyer for a radio transmitter as defined in claim 11 which further includes a source of periodic pulses, a second coupling means, a second artificial line connected between said source of potential and said second coupling means, said second coupling means being also connected to the ignitor electrode-cathode circuits of said ignitrons, and a gaseous discharge path shunting said second artificial line and said second coupling means for periodically discharging said second artificial line through said gaseous discharge path and said second coupling means, the discharge of said second artificial line generating the ignition pulses for said ignitrons.

16. A keyer for a radio transmitter as defined in claim 11 which further includes a second series circuit of: said source of potential, an impedance, a second artificial line and a second coupling means; said second series circuit having parameters making said second circuit a series-resonant circuit, said second coupling means being connected across the ignitor, electrode-cathode circuits of said ignitrons, a gaseous triode shunting said second artificial line and said second coupling means for periodically discharging said second artificial line through said gaseous triode and through said second coupling means, and a source of pulses rendering said gaseous triode conductive in synchronism with the appearance of the maximum charge on said second artificial line.

JOHN E. GORHAM.
WALTER T. SILVER.
